MEANS FOR PREVENTING LUBRICATION SATURATION OF ELECTRICAL MOTORS

Edward J. Ruthman, Cincinnati, Ohio

Original application May 21, 1936, Serial No. 81,043. Divided and this application March 11, 1938, Serial No. 195,372

2 Claims. (Cl. 308—134.1)

This invention relates to improvements in motors, and particularly to means for preventing the saturation of electric motor parts.

This application is a division of an application filed, in the name of Edward J. Ruthman, for Pumps, Serial No. 81,043, on May 21, 1936.

The principal object of the present invention is the provision of an electric motor having bearings which are periodically lubricated, and in which the lubricant is prevented from saturating the parts of the motor.

Another object of this invention is the provision of an electric motor, particularly of the vertical type, that is, with the motor shaft axis disposed vertically, in which means are provided for catching excessive bearing lubricants and disposing of said lubricants to prevent same from endangering the motor parts.

A further object of this invention is the provision, particularly in a vertical type of electric motor, of means for draining off the excess bearing lubricants, and thereby preventing damage to the motor parts.

It is also an object of this invention to provide in a circulating pump, where such pump is used to circulate liquid or fluid in which heavy particles of matter are suspended and said particles capable of separating from the liquid and fluid when quiet, means for freeing the impeller of the pump from the said heavy matter which settles and packs around the impeller when the pump is quiet for a period of time.

Other objects and advantages of the present invention should be readily apparent by reference to the following specification, considered in conjunction with the accompanying drawing forming a part thereof, and it is to be understood that any modifications may be made in the exact structural details there shown and described, within the scope of the appended claims, without departing from or exceeding the spirit of the invention.

In the drawing:

Fig. 1 is a vertical, central section through a self-contained centrifugal pump and motor, embodying the improvements of this invention.

Fig. 2 is a horizontal, sectional, elevational view, taken on line 2—2 of Fig. 1.

Fig. 3 is a fragmentary, sectional view of a portion of the device as illustrated in Fig. 1, and illustrating a modification in the construction.

Throughout the several views of the drawing, similar reference characters are employed to denote the same or similar parts.

By way of example, the invention is illustrated

in connection with an electric motor attached to a centrifugal pump, such as would be used for circulating lubricant, coolant, and the like, on machine tools. As illustrated in the drawing, use is made of a pump housing 10 having formed interiorly thereof the discharge passage 11, which operates in conjunction with the impeller 12. The impeller 12 is keyed or otherwise secured to a shaft 13, which extends centrally of, and into the pump housing 10. The pump housing 10 has 10 projecting from one side thereof a sleeve 14, terminating in a flange 15, which may be utilized for mounting the pump housing in operative position, for example, to the side of a fluid containing tank (not shown). Extending through the 15 mounting flange 15 and sleeve 14 is a passage 16, which is in communication with the upper and lower sides of the impeller 12, and acts as the supply port for the pump.

The pump housing 10 has secured to it, as by 20 means of the flange 17, a connecting standard or housing 18, which is hollow, and has passing therethrough the pump shaft 13. The connecting standard or housing 18 is provided, at its upper end, with a radial flange 19, through which 25 pass suitable bolts or screws for securing there to an electrical motor 20.

The shaft 13 may have connected to it, in any suitable or desirable manner, but preferably integral therewith, the motor shaft 21, which is 30 provided, at its opposite ends, with reduced portions 22 and 23, respectively receiving the inner races of anti-friction bearings 24 and 25. Immediately below the anti-friction bearing 25, the shaft 13 has secured to it a disc 26, acting as a 35 throwout vane, and adapted to intercept mist, spray, or the like, which would rise within the connecting standard or housing 18 due to the agitation of fluid within the pump housing by the impeller 12. The intercepted mist and spray is thrown by means of centrifugal force by the disc 26 through discharge conduit 27 formed in the connecting housing flange 19.

The anti-friction bearing 24 has its outer race pressed into a recess 28, formed in the bell or 45 dome shaped cap 29, integral with the upper cap 30 of the motor 20. The cap 29 is provided, centrally thereof and in line with the axis of the motor shaft 21, with a tapped aperture 31 receiving an "oiling" or lubricating fixture 32. As seen particularly in Fig. 2, the cap 29 is connected with the housing end 30 by means of two posts 33, which may of course be increased in number, but providing comparatively large apertures 34, whereby the interior 55

of the cap 29 communicates with the exterior of the motor.

Secured to the motor shaft 21, between the bearings 24 and 25, is the rotor 35, between the field coils 36 and 37, which are carried by the motor housing ring 38. The lower end of the motor housing ring 38 has connected with it the lower housing 39, which has formed therethrough a plurality of apertures 40 for the admission of cooling air to the motor. The lower motor housing 39, in addition, is provided with a duct or port 41, the outer end of which is tapped, as at 42, for an oiling or lubricating fixture 43. The port or duct 41 communicates with the anti-friction bearing 25 and provides the means whereby this bearing is supplied with lubricant.

The motor shaft 21 has keyed or otherwise secured to it, immediately beneath the anti-friction bearing 24, a fan 44. The fan 44 is provided with a hub 45 from which projects a disc or body portion 46. This disc or body portion 46 is formed in the shape of a dish or saucer, and is so arranged with respect to the bearing 24, as to catch any fluid or liquid, such as lubricating oil, which may drain through the said bearing. Projecting from the lower side of the disc or body 46 are a plurality of fan blades 47, which, when rotating, cause a circulation of air through the motor by drawing or sucking outside air through the motor through the apertures 40 of the motor housing 39. In order to strengthen the fan blades, they may have their lower ends connected by a flange or skirt 48.

The lower wall 49 of the elongated apertures 34, located at the base of the cap 29, is extended inwardly toward the periphery of the fan 44, where it is upwardly turned, as at 50, to provide a lip. The clearance between the inner edge of the wall or ledge 49 and the periphery of the fan 44, is just enough to permit a running fit and without developing any friction heat due to actual contact.

In operation, lubricating oil is introduced to the bearing 24 through the oiling device 32, and the excess lubricant drains through the bearing 25 and is caught by the dish of the fan 44. Centrifugal force throws this lubricating oil outwardly from the dish, which is caught by the inner wall 51 of the cap 29, and from which it drains to the lower wall of the elongated apertures or ledge 49 and flows from there to the exterior of the motor, where it is disposed of. In the event the motor bearing is lubricated while the motor is stationary, and an excessive amount of lubrication is provided, this lubricating oil will of course be caught by the dish 46, and, upon over-flowing, will be caught by the upturned lip 50 or the ledge 49, and again directed to the exterior of the motor where it will be disposed of.

In Fig. 3, a slightly different form of fan is illustrated, in that the fan blades 47 are free of the lower connecting skirt or ring 48, but is provided with the dish 46. In Fig. 3, there is also illustrated the use of the present invention as applied to a motor shaft which projects beyond the motor housing and cap 29. As shown in Fig. 3, the motor shaft 21 is provided with an extension 52 projecting through an opening provided in the cap and projecting beyond the cap. The opening through the cap is provided with a bushing 53 to prevent foreign matter from entering the motor housing. Secured to the extension shaft 52 is a hand wheel or the like 54 which is utilized for a purpose later to be ex-

plained. The shaft extension 52 is provided axially thereof with a small bore or port 55, having secured in its outer end the oiling fixture 56, and the bore 55 having further connection, near its lower end, with a cross port or duct 57, which supplies lubrication to the upper anti-friction bearing 24.

The operation of the slightly modified structure of Fig. 3 is identical with that disclosed in Fig. 1, and above described in detail.

From the foregoing, it will now be appreciated, particularly in connection with vertical type motors, that any excessive fluid or lubricating oil introduced into the motor for the upper bearing, will be promptly arrested and prevented from saturating the motor parts. It will also be appreciated that this excess and arrested lubrication is suitably discharged from the motor and disposed of exteriorly thereof. These safeguards are provided for the motor parts, whether the motor is stationary or running at the time that the lubricant is supplied to the bearing.

In addition, the fan 44, while rotating immediately behind the apertures 34, acts as a wall and throw-out to any foreign material that attempts to enter the motor through these apertures. This is especially valuable when a hose is utilized around the machine on which the motor is mounted and which may be turned on the pump for cleaning purposes and the like.

The self contained motor pump of Fig. 1, when modified as illustrated in Fig. 3, is utilized for the circulation of liquids or fluids that have suspended therein heavy particles of matter, such as abrasive fluids, chalky fluids, white wash and similar materials. When the pump is shut down, as for example, over night or over the week-end, these heavy particles settle out of the liquid or fluid and pack around the impeller within the pump housing, and frequently hold the motor from starting the pump when the current is first turned on. In order to start the pump, the operator would grasp the hand wheel 54 and oscillate or rotate the motor pump shaft 13-21, and thereby loosen the particles around the impeller so that the motor 20 could then rotate the impeller and start a circulation of the liquid or fluid. Sometimes these circulating pumps are employed with fluids or liquids that are prone to rust, and a shut-down of the pump causes a slight film of rust to form and hold the parts against starting by the motor 20, but a slight pressure on the shaft through the hand wheel 54 breaks the rust hold so that the motor can then operate as usual. In addition, the hand wheel may serve as a medium to indicate to the operator that the motor is running and the pump operating.

What is claimed is:

1. In a device of the class described, the combination of a motor housing including upper enclosing walls, a vertical shaft within said housing, a bearing for the shaft supported by the housing upper walls, means for supplying lubricant through the housing to the bearing, a dish shaped receiver upwardly and outwardly flared carried by the shaft below the bearing adapted to receive the lubricant as it passes from the bearing, said dish shaped receiver being enclosed by said housing upper walls against which the lubricant is thrown by centrifugal force upon rotation of the shaft, a ledge integral with the motor housing and projecting inwardly thereof and having its inner edge upturned

and closely adjacent the periphery of the dish shaped receiver, said ledge being adapted to receive overflow of lubricant from the dish shaped receiver and to receive the lubricant as it drains 5 from the housing walls, and ports through the motor housing in line with the ledge through which the lubricant flows outwardly.

2. In a device of the class described, the combination of a motor housing, a vertical shaft 10 within said housing, a bearing for the shaft supported by the housing, means for supplying a lubricant through the housing to the bearing, a combined dish shaped receiver and fan carried by the shaft below the bearing adapted 15 to receive the lubricant as it passes from the bearing and to circulate cooling air through the motor housing, said dish shaped receiver

and fan being enclosed by the walls of the motor housing against which the lubricant is thrown by centrifugal force upon rotation of the shaft, a ledge integral with the motor housing and projecting inwardly thereof and having its inner 5 edge upturned and closely adjacent the periphery of the dish shaped receiver and fan, said ledge being adapted to receive overflow of lubricant from the dish shaped receiver and to receive the lubricant as it passes from the 10 housing walls, and ports through the motor housing in line with the ledge through which the lubricant flows outwardly and through which ports the air circulated by the fan is discharged into the atmosphere.
